UNITED STATES PATENT OFFICE.

GEORGE E. BROWNE, OF GREENFIELD, MICHIGAN.

FLOWER-SUPPORT.

No. 899,946.

Specification of Letters Patent. Patented Sept. 29, 1908.

Application filed December 13, 1907. Serial No. 406,256.

To all whom it may concern:

Be it known that I, GEORGE E. BROWNE, a citizen of the United States, residing at Greenfield, county of Wayne, State of Michigan, have invented a certain new and useful Improvement in Flower-Supports, and declare the following to be a full, clear, and exact description of the same, such as will enable others skilled in the art to which it pertains to make and use the same, reference being had to the accompanying drawings, which form a part of this specification.

This invention relates to flower supports, and has for its object an improved support in which there is combined a hoop to surround the plant and a standard on which the hoop can be adjustably secured at any convenient height or place along said standard.

In the drawings:—Figure 1, shows the hoop supported by a doubled wire support. Fig. 2, shows a single standard support.

The standard consists of a wire 1, the main part of which consists of two parallel members A and B, formed by bending the wire at its middle point C, and extending the members A and B, parallel with each other for a distance sufficient to make the desired length of standard. The two members A and B, are then twisted together at D, the ends spread to furnish width of base, and fork members E and F formed; which fork members are adapted to be driven into the ground to furnish the means by which the standard is held in an upright position.

The hoop member consists of a single wire 2, provided with rectangular loops at each end. The loop 3, at one end of the wire has a cross bar 4, which joins the main body part 5 of the hoop and the parallel member 6, of the hoop with small confining bends arranged to allow the proper engagement between the hoop lock and the standard, and in order that the proper lock may be produced between the parts, there is formed at the intersection of the cross bar and the body part of the hoop at one end of the cross bar, a bend 7, having a depth of about half the thickness of the wire of the standard; continuous with this bend 7 is a second projecting bend 8, of somewhat more than the thickness of the wire of the hoop. The extreme space spanned by the two bends last mentioned should as nearly as possible equal the combined thickness of the standard wire and the hoop wire. At the intersection of the

cross bar 4, and the parallel member 6, of the hoop, there is a bend 9 and a second bend 10 exactly similar in character. On the other end of the hoop than that on which is made the rectangular loop just described, is made a second rectangular loop, or substantially rectangular loop, extending for a considerable distance parallel with the main wire 5 of the hoop. The distance from the main wire 5 to the member 12, is narrower than the distance between the main wire 5 and the member 6, and is made so that the main wire 5 and the wire of the member 12, may engage closely within the boundaries of the projecting bends 8 and 9. When thus constructed the hoop and the standard will interlock, the standard forming an interlocking member to retain the loops in their interlocked condition, and the hoop by reason of the bends 7 and 9, will assume a position at right angles to the axis of the standard and will maintain the position with stability. Preferably bends 13, 14, are made to engage the parallel member B of the standard. The bends 13, 14, may be omitted, but I prefer to use them.

To produce the interlocked condition, the hoop is brought into engagement with the standard, the member A, of the standard engaging in the hollow of the bends 7 and 10, and with the standard B, bearing against the members 5 and 8. The end 15, of the second loop is inserted under the hollow of the projecting loops 8 and 9, and this loop is then pushed across the members of the standard, and the end 15, is brought under the cross bar 13 of the first loop. The second or narrower loop may be adjusted across the first or broader loop, and the interposed standard, to adjust the size of the hoop to any suitable size within the limits of the adjusting loop. Any number of hoops desired may be placed on the standard. The same construction of hoop may be used with a single standard corrugated support G.

What I claim is:—

1. A plant support, having in combination a standard, and a hoop provided with parallel membered loops overlapping one another at each end and originally out of interlocking position the one with the other, that part of each loop adjacent to the standard being forced out of its normal vertical plane toward the plane of the other loop by the interposition of the standard, whereby

they and thereby the hoop are resiliently locked in position therealong, substantially as described.

2. A plant support, having in combination a standard, an open hoop, each of whose ends is bent upon itself to constitute parallel branches of a terminal loop, said looped portions being adapted to overlap and to be locked in position with respect to one another and to said standard by the engagement of the same between the portions of the overlapping ends, each looped portion being forced thereby toward the other against the resilient pressure of such other, substantially as described.

3. A plant support, having in combina-

tion with a standard, a hoop, a portion of whose peripheral extent is quadrupled by the looping of each end of the wire constituting the hoop and the overlapping of said looped portions, said standard being adapted to be inserted therebetween and to thereby interlock therewith, each looped portion being bent toward the other against the opposing resilient pressure thereof, substantially as described. 20 25

In testimony whereof, I sign this specification in the presence of two witnesses.

GEORGE E. BROWNE.
